W. L. FRIEDMAN.

UNITED STATES PATENT OFFICE.

WILLIAM LLOYD FRIEDMAN, OF OAKLAND, CALIFORNIA.

DETACHABLE HAT-PIN HEAD.

1,020,754.

Specification of Letters Patent. Patented Mar. 19, 1912.

Application filed January 24, 1911. Serial No. 604,491.

To all whom it may concern:

Be it known that I, WILLIAM LLOYD FRIEDMAN, a citizen of the United States, residing at Oakland, in the county of Alameda and State of California, have invented 5 a new and useful Detachable Hat-Pin Head, of which the following is a specification in such full and clear terms as will enable those skilled in the art to construct and 10 use the same.

This invention relates to a new and useful hatpin guard intended for the purpose of protecting the owner thereof from the loss of hatpins and also intended to prevent 15 the point of the hatpin from striking persons other than the wearer thereof and injuring them.

It will be understood that ladies wear 20 hatpins of considerable length, one end of the pin projecting oftentimes a considerable distance from the hat, thus endangering the eyes and faces of persons near.

Another object of the invention is to provide 25 a guard which will be applicable to any hatpin, the catch therein holding a smooth surface such as the end of the ordinary hatpin presents.

In the drawing in which the same numeral of reference is applied to the same 30 portion throughout the several views, Figure 1 is a side elevation of a hat pin having a permanent head at one end and a detachable guard thereon at the other. Fig. 2 is a side elevation of a removable head 35 having the pin securing catch applied thereto, and Fig. 3 is a sectional view on an enlarged scale through the tube end in which the pin is inserted when it is desired to secure the hatpin to the hat.

The numeral 1 is applied to the pin 40 proper; 2 representing the permanent head secured thereto. At the pointed end, the pin has a head 3 which may be of any suitable contour as desired. This head has a 45 plate 4 secured thereto which is provided with a short tube 5 near the center thereof. This tube 5 is intended to be of substantially the same size as the pin of the ordinary hatpin, and it has one end closed, as 50 at 6, the object being to force the pin up against the catch when it is inserted in the

sleeve 5 should the pin be smaller than the tube. On one side the tube has an opening therein, as shown at 7.

Secured to the plate 4 is a spring 8 which 55 has a finger button 9 to move the same and the end of said spring passes into the slot 7 in the tube 5. This spring is of such length as to touch the pin when the same is inserted in the sleeve 5, but it does not prevent 60 the pin from being pulled out of the sleeve, since its end can only move back by striking a small arc which the metal of the pin prevents, this making impossible the removal of the pin from the sleeve 5 unless 65 the finger catch 9 is pushed in, which at once releases the pin and permits the removal thereof from the sleeve 5.

It will be understood by those skilled in the art that the head 3 may be made in any 70 one of a number of different forms, as may be desired. The form of the head however, is only dependent upon the desire of ornamentation of the wearer.

Having thus described my invention what 75 I claim as new and desire to secure by Letters Patent of the United States, is as follows:

In a removable hatpin head, an ornamented member, a sleeve adapted to receive 80 the pin and having a notch cut in one side thereof, the inner end of the sleeve being housed in the member, a bar extending at right angles to said sleeve and securing the latter to the ornamented member, a spring 85 secured to said bar and having one end thereof projecting into the notch in the sleeve and being adapted to contact with a pin 90 slidable in said sleeve to hold the same therein, and a pin connected with said spring and extending through said bar to move said spring longitudinally of said sleeve to release the pin, substantially as described.

In testimony whereof I have hereunto set 95 my hand this 12th day of January A. D. 1911, in the presence of the two subscribed witnesses.

WILLIAM LLOYD FRIEDMAN.
